UNITED STATES PATENT OFFICE.

JOHN M. DAVIS, OF ROCHESTER, INDIANA.

SPRING-SEAT.

SPECIFICATION forming part of Letters Patent No. 247,319, dated September 20, 1881.

Application filed May 26, 1881. (Model.)

To all whom it may concern:

Be it known that I, JOHN M. DAVIS, of Rochester, in the county of Fulton and State of Indiana, have invented certain new and useful 5 Improvements in Spring-Seats; and I do hereby declare that the following is a full, clear, and exact description of the invention, which will enable others skilled in the art to which it appertains to make and use the same, reference being had to the accompanying drawings, which form a part of this specification.

Figure 1 is a top view of my improved wagon-seat, and Fig. 2 is a vertical sectional view.

Similar letters of reference indicate corresponding parts in both figures.

This invention relates to spring-seats; and it consists in certain improvements in the construction of the same, which will be hereinafter fully described, and particularly pointed 20 out in the claim.

In the drawings hereto annexed, A represents a suitable board or plank, forming the base or bottom of the seat.

B B are conical spiral coiled springs, which 25 are arranged in rows, as shown, upon the board A, to which they are secured by staples C or in any other suitable manner. The upper coil of each spring is interlaced with the upper coils of the adjoining springs, as shown, so as 30 to form a complete woven-wire mat, which forms the top of the seat. By thus interlacing the coils each individual spring is retained securely in the proper position in which it is originally placed.

The back of the seat consists of a wooden 35 rod, D, supported upon iron rods E E, bent at their lower ends, so as to project under the board A, to which they are secured by screws or bolts. The upper ends of the rods E are driven into the bar D, and fastened by pins F, 40 driven through said bar and through eyes G at the upper ends of rods E.

The arms of the seat are formed of round iron rods H, bent into S shape, as shown, and secured to the under side of board A and to 45 the ends of bar D.

By this invention a simple, durable, and comfortable seat is provided, for the top of which no covering is necessary, although, of course, any desired flexible or textile cover 50 may be provided.

I am aware that coiled and spiral springs have been before used for various purposes, and such is not sought to be broadly covered in this application; but

What I do claim is—

The wagon-seat herein described, consisting of the base A, standards E, back D, spring-arms H, and interlocked and interwoven spiral springs B C, secured upon the base A, as and 60 for the purposes set forth.

In testimony that I claim the foregoing as my own I have hereto affixed my signature in presence of two witnesses.

JOHN M. DAVIS.
